UNITED STATES PATENT OFFICE.

DAVID T. MILLS, OF DAYTON, OHIO.

PULP-GRINDER.

SPECIFICATION forming part of Letters Patent No. 393,075, dated November 20, 1888.

Application filed February 4, 1888. Serial No. 203,040. (No model.)

To all whom it may concern:

Be it known that I, DAVID T. MILLS, a citizen of the United States, residing at Dayton, in the county of Montgomery and State of Ohio, 5 have invented certain new and useful Improvements in Pulp-Grinders, of which the following is a full, clear, and exact description, reference being had to the accompanying drawings, forming part of this specification.

10 My invention relates to that class of machinery known as "wood-pulp grinders;" and it consists in certain details of construction and combinations of parts, which will first be described in connection with the drawings, and 15 then pointed out in the claims.

In the accompanying drawings, Figure 1 is a side elevation of one of my improved grinders, partly in section and with a portion of the casing broken away. Fig. 2 is a sectional end 20 elevation of the same. Fig. 3 is a perspective view of the presser-box. Fig. 4 is a side elevation of the same.

The same letters of reference are used to indicate identical parts in all the figures.

25 The casing A of the grinder may be of the usual or any suitable construction, and is in this instance supported on a brick foundation, within which is the usual pit for the collection of the ground pulp. The stone B is hung on 30 a shaft, C, journaled in boxes or pillow-blocks D, which rest upon overlapping oppositely-set wedges E within a frame, F. By means of set-screws a, tapped through the frame F and bearing against the heads of the wedges, the 35 latter may be adjusted to maintain the shaft C in proper vertical alignment, while by means of other set-screws, b, tapped through the frame F and bearing against the blocks D, the shaft can be adjusted to keep it in proper 40 horizontal alignment.

The block-pressers are composed of the usual or any suitable hydraulic cylinders, G, secured to the casing and supplied with pistons and piston-rods H, extending through stuffing-boxes at both ends of the cylinders. For each cylinder there is a presser-box, I, Fig. 3, adjustably hung within the grinding-frame by means of collar-bolts e, Fig. 2, and held from movement in any direction, except longitudinally, by ribs d, projecting from the inner 45 sides of the grinder-casing against the corner

edges of the box. These boxes may be tapered—that is, enlarged inside at their lower ends—to prevent the binding of the wood, if desired. Where square blocks are used tapering is not necessary. The front ends of the boxes are provided with offsets e, opposite which grooves f are cut on the inner side, extending from the top to the bottom of the box—that is to say, parallel with the piston-rods— 55 to receive set-screws or pins g, extending from the presser-platens J, secured to the lower ends of the piston-rods H to prevent the binding of said rods. The sides of the boxes opposite the usual doors, K, in the casing A for the insertion of the wood are provided with openings, and at the bottom of said openings flanges h are provided either integral with the box, as shown, or secured to the casing A. These flanges are some distance above the periphery 60 of the stone, and, with the lower side walls of the boxes, serve to prevent the escape of pulp and water when the doors are opened. The lower edges of the side walls of the boxes conform to the curvature of the stone, but are 65 sufficiently above it to permit the escape of the ground pulp over the sides of the stone into the pit below. The lower edges of the front walls of the boxes are in close proximity or working contact with the stone, while the lower 70 edges of the rear walls are some little distance above the stone, as seen in Fig. 1, to permit any unground slivers or shims that may escape from one box to be carried by the revolution of the stone under such rear edges into the 75 next box, where they will be converted into pulp. Without this provision the shims would accumulate between the boxes and prevent the proper spraying of the stone. By means of the collar-bolts c the boxes may be adjusted from 80 time to time as the stone wears down to keep 85 them in constant proper working position.

The piping for the admission of the water to the cylinders to actuate the pistons may be of the usual or any suitable construction. I have 90 illustrated it as in three banks for each machine secured by clips to the sides of the cylinders, of which the upper pipe, L, is the influent pipe, the next lower, M, the effluent pipe, and the lower one, N, the pipe which admits 95 100 the spraying-water from any desired source through branches h' and perforated cross-pipes

i, arranged between the boxes I and across the face of the stone. The pipes *i* extend at one or both ends through the casing A, and are provided with removable caps *j* to give access to the pipes when it is necessary to clean them, for it frequently happens that water from the wet machine is employed to spray the stone, and the perforations in the pipes *i* sometimes become clogged.

10 *c* Each cylinder is provided with the usual or any suitable ports and a four-way or other suitable valve, into which a branch, *k*, from the pipe L extends, and from which a branch, *l*, extends to the pipe M for directing the water from the influent pipe to either end of the cylinder or for cutting it out of action when desired.

The water-supply may be taken from any source with the requisite pressure.

15 *o* Having thus fully described my invention, I claim—

1. In a wood-pulp machine, the combination, with a stone, a casing over the stone provided with one or more doors, and one or more block-pressers applied to said casing, of a presser-box for each block-presser supported within the casing and provided with an opening coincident with its door in the casing to permit the introduction into said box of the blocks to 25 be ground, substantially as described.

2. In a wood-pulp machine, the combination, with a stone, a casing over the stone provided with one or more doors, and one or more block-pressers applied to said casing, of a presser-box for each block-presser adjustably supported within the casing and provided with an 30

opening coincident with its door in the casing to permit the introduction into said box of the blocks to be ground, substantially as described.

3. In a wood-pulp machine, the combination, 40 with a stone, a casing over the stone provided with one or more doors, and one or more block-pressers applied to said casing, of an interiorly-tapering presser-box for each block-presser supported within said casing and provided 45 with an opening coincident with its door in the casing to permit the introduction into said box of the blocks to be ground, substantially as described.

4. In a wood-pulp machine, a stone and a 50 presser-box to receive the blocks to be ground, having its lower front edge in close proximity or working contact with the stone, its lower rear edge raised above the surface of the stone to permit the passage of shims, its lower sides 55 conforming to the curvature of the stone, and an opening in one side to permit the introduction of the blocks to be ground, substantially as described.

5. The presser-box I, provided with the offsets *e*, grooves *f*, an opening in one side to permit the introduction of the blocks to be ground, and the flange *h* at the lower side of said opening, in combination with the casing A, collar-bolts *c*, ribs *d*, and the presser-platen provided 60 with set-screws or pins entering the grooves *f*, substantially as and for the purpose described. 65

DAVID T. MILLS.
